UNITED STATES PATENT OFFICE.

FRANK G. SMITH, OF ELIZABETH, NEW JERSEY.

APPLIANCE FOR SECURING RAILS UPON THE TIES OF A RAILROAD.

1,082,977.

Specification of Letters Patent. Patented Dec. 30, 1913.

Application filed October 16, 1912. Serial No. 726,162.

To all whom it may concern:

Be it known that I, FRANK G. SMITH, a citizen of the United States of America, residing at Elizabeth, State of New Jersey, have invented a certain new and useful Appliance for Securing Rails Upon the Ties of a Railroad.

My invention relates to improvements in appliances for fastening and maintaining the rails upon railroad ties and may be used in combination with wood, metal or cement ties.

In the accompanying drawings I have illustrated in Figure 1 an application of my invention as applied to a wooden tie. Fig. 2 is an enlarged view in perspective partly broken away and partly in cross section showing some of the details, and Fig. 3 is another view partly in cross section showing 20 the rail locked in position upon the plate which is to be secured to the tie.

4 indicates the wooden tie usually laid in the road bed of the railroad, and 5 the metallic plate which may be suitably secured 25 or held thereupon by suitable means such as the lugs 6 and by spikes or other suitable means which may be driven through the openings 7. 8 are additional lugs or flanges stamped out of the plate 5 which also penetrate the tie 4, to give additional security or hold to the plate.

9 indicates in dotted outline the position of the base of the rail such as 10 and it will be observed that the lugs 11 engage the base 35 flange 12 of the rail which is held thereunder by the lips or projections 13 also stamped out of the plate 5. In order to prevent the rail from becoming loosened a suitable securing bar such as 14 may be employed. This bar preferably passes beneath 40 the lug or lip 15 at one side and the lug or

lip 16 at the other side, both of which are preferably punched out of the plate 5, one end of said bar being turned upwardly to engage the base 12 of the rail 10 as indicated 45 at 19, and the other end preferably terminating in a hook formation such as 17 to engage the opening or port 18 in the plate 5 as shown to better advantage in Fig. 3, the bar 14 being sufficiently resilient to be forced 50 over the plate 5 and beneath the lugs or lips 15-16 until the end of the hook portion 17 snaps into the opening 18 thus securely holding the combination in position. To remove the fastening means it is then necessary to pry up the hook portion 17 with a crowbar or other suitable means.

Of course it will be understood that various modifications may be made in the general arrangement and structure of the several parts without departing from the spirit of the invention as claimed.

I claim:

In combination with the rail and tie of a railroad, a plate adapted to be secured to the tie, and means in combination therewith for securing the rail thereupon, said means comprising lugs stamped out of said plate engaging the base of said rail, a bar adapted to engage other lugs stamped out 70 of said plate and also to engage the base of said rail, and means in combination with said plate and said bar whereby the same are interlocked after said rail and said bar have become engaged.

In witness whereof I have hereunto affixed my signature.

Dated, New York, September 13, 1912.

FRANK G. SMITH.
